UNITED STATES PATENT OFFICE.

ARTHUR P. STRONG, OF CHICAGO, ILLINOIS, ASSIGNOR TO GREEN ENGINEERING COMPANY, OF EAST CHICAGO, INDIANA, A CORPORATION OF ILLINOIS.

FURNACE.

1,242,263.

Specification of Letters Patent.

Patented Oct. 9, 1917.

Application filed March 8, 1917. Serial No. 152,635.

To all whom it may concern:

Be it known that I, ARTHUR P. STRONG, a citizen of the United States, residing at Chicago, in the county of Cook and State of Illinois, have invented new and useful Improvements in Furnaces, of which the following is a specification.

This invention relates to improvements in furnaces of steam boilers, and more particularly to the construction of a furnace stoker of the mechanical type, preferably embracing an endless traveling chain grate and the novel features pertaining to means for supplying air to the fuel bed supported upon the grate, either in the form of natural or forced draft.

In the operation of steam boiler furnaces, the use of a forced draft is well recognized as desirable under variable load conditions, where the rapid promotion of combustion is necessary to meet sudden increases of load upon the boiler. This is particularly true in boiler plants where the so-called peak loads must meet at certain periods of comparatively short duration. From the standpoint of economy and efficiency of operation, it is essential that the steaming capacity of the boiler be increased to meet the load, in the shortest interval of time. On the other hand, it is equally essential, to efficient and economical performance, to utilize the natural draft under normal conditions of operation, thus making it unnecessary to operate the forced draft fan or blower and the auxiliary operating units.

It is apparent, therefore, that a desirable arrangement is the combination of both forced and natural draft, together with means for shifting from one to the other. It is to such an arrangement that this invention relates and embodies a system of air ducts or passages located beneath the grate surface and communicating with suitable supply ducts, together with dampers designed to be opened when the furnace is being operated under forced draft, simultaneously closing the passages whereby the natural draft is supplied to the grate surface, and, vice versa, operative to close the forced draft ducts and to permit the entrance of natural draft to the grate surface.

A preferable construction embodying the features of the invention is herein illustrated and described in connection with a

so-called chain grate stoker of the removable type, that is, the stoker unit being mounted on suitable trucks, thereby permitting the stoker to be drawn out from the furnace for the purpose of inspecting or the making of repairs. A stoker of this type, together with portions of the furnace necessary to a complete understanding of the invention, is herein described and fully illustrated in the accompanying drawings, in which—

Figure 1 is a view in longitudinal section of a furnace and stoker embodying the features of the invention;

Fig. 2 is an enlarged detail view in longitudinal section, taken on line 2—2 of Fig. 4, showing the arrangement of dampers and operating devices;

Fig. 3 is a view in side elevation of one of the lateral air boxes removed, and showing the arrangement of ducts and outlets therein;

Fig. 4 is a view in transverse section of the stoker, taken on line 4—4 of Fig. 2;

Fig. 5 is a perspective view of one pair of cross-ducts, showing dampers and operating devices;

Fig. 6 is an enlarged detail view of the damper operating members;

Fig. 7 is a detail view of the damper operating levers; and

Fig. 8 is a detail view of the connecting members between the lateral air boxes and main supply duct, and showing the arrangement of control dampers therein.

A steam boiler furnace of the type to which this invention is applicable, comprises the usual brick structure or setting, embracing side walls 10, 10, a front wall 11, and a coking breast 12 extending inwardly and over the forward end of the fuel bed support 95 on the grate, hereinafter to be described. Rearwardly of the front wall and centrally of the furnace, is a vertically extending, transverse bridge wall 13, the space intermediate the front wall and the bridge wall 100 constituting the combustion chamber of the furnace. Above the combustion chamber are the boiler tubes 14 of the steam boiler, of the water tube type, said tubes being mounted at their ends in headers, the front header 15 being shown as supported immediately above the coking breast 12.

Within the combustion chamber and ex-

tending outwardly therefrom in front of the furnace is the stoker, comprising main parts as follows: A traveling chain grate 16, comprising a multitude of hinged together 5 links forming a flexible endless belt of short grate bars, is supported upon a frame structure including the feeding devices, all of which is mounted on trucks, permitting the entire stoker to be withdrawn from the furnace. The frame structure comprises, in general, two vertical side frame members 17, having the form of longitudinally extending plates arranged in parallel relation at the sides of the stoker and connected together 10 by a plurality of transverse beams or girders 18, spaced apart at suitable distances throughout the length of the side frame members. The location and formation of these transverse girders will hereinafter be 15 described in detail. The side frame members and transverse girders form the main grate-supporting structure, which is, in turn, supported upon the floor or foundation of the furnace by means of trucks 19, located inwardly from the front and rear ends of the stoker frame, and comprising flanged wheels 20 mounted upon journal shafts 21, the latter being mounted in suitable journal bearings 22 provided along the lower edges of the side 25 frame members. The wheels 20 rest upon tracks 23, having the form of the usual T-rail, which extend throughout the length of the grate and a sufficient distance outwardly 30 from the front of the furnace, thereby permitting the entire stoker to be removed from the furnace.

At the front and rear ends of the stoker frame are rotatably mounted sprocket shafts 24 and 25, respectively, said shafts being 40 supported at their ends in suitable bearings formed in the side frame members 17, said shafts carrying a plurality of sprocket wheels 26, which mesh with the grate and movably support the same. Mounted on 45 the front sprocket shaft 24 is a gear wheel 27 (Fig. 1), which meshes with a train of reduction gear wheels (not shown) mounted upon the stoker frame adjacent the front end of the grate, said gear train having 50 operative connection with a suitable prime mover, whereby power is transmitted through said gear train to rotate the front sprocket shaft, thus imparting movement to the grate in a direction to advance the fuel 55 bed, supported upon the upper lead of the grate, in a direction from the front toward the rear of the combustion chamber. Intermediate the sprocket shafts and spaced at suitable distances apart throughout the 60 length of the grate, are provided a plurality of transverse supporting rollers 28 and 29, which support the upper and lower portions of the grate, respectively. The upper rollers 28 are journaled in bearings 30 (Fig. 4) provided along the upper margins of the side

frame members, and the lower rollers 29 similarly journaled in bearings 31 located above the lower margins of said side frame members.

The forward end of the stoker frame comprises vertical side plates 32, located exterior of the furnace and in the plane of the side frame members 17, said plates extending upwardly above the front end of the grate and in contact with the front wall 11. Extending between the side plates 32 is a front plate 33, supported in a downwardly inclined position and terminating above the grate surface, said front and side plates forming, with the front wall of the furnace, the fuel hopper of the stoker. The fuel hopper communicates with the mouth of the furnace, formed between the lower face of the front wall and the surface of the grate, said mouth being capable of variation, as to size, by the provision of a vertically movable gate 34, mounted above and in front of said mouth.

Adjacent the rear end of the furnace are further provided stop members 35, 35, comprising vertically extending frames rigidly mounted in the floor of the furnace adjacent each side frame member, each provided with an inclined and forwardly facing beam 36 adapted to engage a similarly inclined flange 37 on the outer faces of the side frame members. The stop frames are adapted to engage the stoker frame and to thus determine the position of the stoker within the furnace by preventing the rearward movement of the stoker beyond its proper or predetermined position.

Referring now to the arrangement of the draft ducts embodying the features of the invention and associated with the stoker, there are located in that portion of the grate within the combustion chamber, and between the upper and lower portions or leads of the grate, a plurality of transverse or cross-ducts, said ducts being arranged in pairs, the ducts of each pair being associated with and separated by each of the girders 18, as will now be pointed out in detail. As shown in the drawings, there are four girders 18 within the space between the upper and lower leads of the grate and between the rear end thereof and the front wall 11 of the furnace, each girder being located immediately below alternate rollers 28, that is, the foremost girder extends downwardly in the vertical plane of the roller just within the combustion chamber, the second being similarly located below the third roller, the third girder being located below the fifth roller in front, and the fourth girder being located adjacent to the rearmost roller. Inasmuch as all of the air ducts illustrated are similar in construction, with the exception of the rearmost air duct, the description of the construction of one pair of ducts or unit will suffice for all.

Referring to the formation of the front-most pair of cross-ducts (Fig. 2), the same are formed, as hereinbefore suggested, by utilizing the girder 18, the same having a cross-sectional contour of an inverted T, comprising a vertical web 38, which terminates substantially in contact with the under-surface of the adjacent roller 28, and extends downwardly to a point just above the lower portion or lead of the grate, there being provided an integral transverse web 39 extending forwardly and rearwardly from the vertical web equal distances therefrom, the outer margins of said horizontal web being provided with short, upwardly extending flanges 40. Mounted on the upper margins of the flanges 40, 40 of the girder are dampers 41, 41, comprising metal plates connected to said flanges by means of hinges 42. The damper mounted at either end of the transverse web 39 of the girder and on either side of the vertical web 38 thereof, extends transversely between the side frame members 17 and upwardly in an inclined direction toward each other, terminating at their upper margins in close proximity to each other, and, when in normal or closed position, as shown in full lines in Fig. 2, bear against opposite sides of the associated roller 28. From this description it will be seen that there is formed on opposite sides of the vertical web 38 of the girder, a pair of separate air ducts 43, 43, said vertical web forming the rear wall of each duct, the horizontal web forming the bottom wall of each duct, and the dampers 41 forming the outer movable wall thereof, when in contact with the roller 28. Associated with the second and third inverted T shaped girder are similarly formed pairs of air ducts 44, 44 and 45, 45, respectively, likewise provided with hinged dampers 41, 41, identical with those heretofore described. The dampers 41, 41 of each pair of ducts are adapted to be swung simultaneously in a direction outward from the adjacent roller and through an angle of substantially 45° to the dotted line position shown in Fig. 2, the movement of said dampers being limited by their contact with the rollers 28, 28, located intermediate the girders 18. The movement of the dampers to the dotted line position effects the opening of the ducts to permit the admission of the forced draft to the grate, it being observed that when all of said dampers are in open position, that is, in contact with the intermediate rollers, the space included between each pair of dampers is entirely shut off from communication with the space below the grate, and thus no air but that which is forced through the ducts can be admitted to the grate.

These dampers are operated by manually controlled devices, hereinafter described, although the dampers associated with each

pair of ducts are controlled as a single unit and independently of the other sets of dampers.

Referring to the rearmost duct 46, the same is formed by the rearmost girder 18, which has a vertical web 40 offset rearwardly from the adjacent roller and terminating in contact with the rear surface thereof and a single horizontal web, which extends forwardly from the vertical web 48, as before. The damper 41 of said rearmost duct is of the same construction as before described; in fact, the duct is quite similar in all respects to a single duct of the pair of ducts heretofore described. Furthermore, inasmuch as the rearmost girder 18 closes the draft delivery space of the grate, the vertical web terminates to the rear of the roller and in contact therewith, as described, for the purpose of sealing said space from the open space to the rear of the furnace.

Referring now to the means employed for supplying air to the transverse cross ducts from a main source of supply, such as a blower or like apparatus located exterior of the furnace, there are provided longitudinally extending, lateral ducts or air boxes 50, 50, mounted on the stoker frame and extending longitudinally along the outside of the side frame members 17, 17, adjacent the ends of the cross ducts. These air boxes preferably comprise rectangular sheet metal conduits fastened against the outside surfaces of the frame members and extending from a point just forward of the front pair of cross ducts 43, 43 rearwardly beyond the rear end of the grate, and adapted to have contact with the front surface of the bridge wall 13, there being provided connections between the rear ends of the air boxes and a main supply duct, as will hereinafter be pointed out. The air boxes are divided into a plurality of separate longitudinal ducts, the corresponding ducts of each air box communicating with the ends of each pair of cross ducts, as will be understood from the following: Mounted within each air box and spaced below the top wall thereof, is a partition wall 51 (Figs. 3 and 4) extending throughout the length thereof and transversely between the vertical side walls of the box, although inclined upwardly from the outer wall thereof. In this manner there is formed above the partition wall 51 a duct 52, which is closed at its outer end by the end wall or closure 53. The duct 52 of each air box communicates with the ends of the front pair of cross ducts 43, 43 by means of openings 54, 54 in the side frame members, which register with corresponding flanged openings in the air boxes. Below the partition wall 51 in each air box is another partition wall 55, also extending longitudinally of each air box and substantially midway of the height thereof, said partition

wall 55 and partition wall 51 forming between them an air duct 56 extending from the rear end of each air box to a point just forward of the next rearward pair of cross ducts 45, 45, there being provided just beyond said pair of ducts a vertical end wall 57. Each duct 56 communicates with its associated pair of cross ducts 44, 44 by means of an opening 58 having a height equal to 10 the distance between the inner margins of the partition walls 51 and 55 and communicating with the cross duct just below the upper duct 52. In the same manner, a third longitudinal duct 59 is formed, by means 15 of a partition wall 60, which extends vertically upward from the bottom wall of each air box and is then inclined inwardly and upwardly, terminating a short distance below the inner margin of the partition wall 20 55, the air duct 59 thus formed having a somewhat irregular shape and extending forwardly from the rear end of the air box just beyond the next rearward pair of cross ducts 45, 45, and being closed at its end by a 25 vertical end wall 61. Each duct 59 communicates with its associated cross ducts by means of openings 62 having a height equal to the distance between the inner edges of the partition walls 60 and 55. The remaining 30 portion of each air box, inwardly and below the partition wall, forms a fourth duct 63, which is included between the partition wall 60 and the bottom and side walls of the air box, said duct extending forwardly 35 from the rear end of the air box a short distance beyond the rearmost cross duct 46, where it is closed by means of an end wall 64, said cross duct being provided with an opening 65 adjacent the lower portion thereof 40 and having a height equal to the distance between the surface of the girder web 49 and the edge of the partition wall 60.

The rear ends of the air boxes 50, 50 communicate with a main supply duct 66 mounted transversely behind the vertical bridge wall 13 and supplied with air from a suitable blower mechanism, as hereinbefore stated. As a means for connecting the air boxes with the main cross duct, there is embedded in the bridge wall a connecting fitting 67 (Figs. 2 and 8) having the same cross-sectional arrangement of partition walls as the air boxes, and, in short, forming a continuation of said air boxes and air ducts therein. Inasmuch as the stoker is removable from the furnace, it is desirable that the air boxes be removably connected at their rear ends to connecting fittings 67, 67 embedded within and extending through the bridge wall, there being employed suitable flange connections, as at 68, between the abutting ends of the air boxes and connecting fittings, whereby the same can be disconnected when it is desired to withdraw 85 the stoker from the furnace. Within each

connecting fitting 67 are provided a plurality of dampers 69, there being mounted a damper in each of the passages of said fitting associated with the several air ducts of the air box. These dampers have substantially the same shape as the cross-sectional contour of the several air ducts, and are rotatively mounted upon horizontal shafts journaled in bearings of any suitable form, and when in vertical position are 70 adapted to completely close the air ducts from the main supply air duct 66. The shafts supporting the several dampers 69 have lateral extensions in the form of rods 75 70, preferably extending through the side wall 10 of the furnace, and are provided with operating members operative from the exterior of the furnace, so that each damper or corresponding pairs of dampers can be manipulated independently of each other, 80 thus permitting an accurate control of the draft to each pair of cross ducts. Thus, when the furnace is being operated under forced draft, the amount of air supplied to the several portions of the grate area 85 served by the several pairs of cross ducts, can be accurately regulated, and the firing conditions throughout the grate area can be controlled as desired.

Referring again to the several pairs of cross ducts and the dampers associated therewith, it has been hereinbefore pointed out that the dampers associated with each pair of ducts are adapted to be operated simultaneously with respect to each other, 90 but independently of the dampers of the other pairs of cross ducts. As a preferable means for operating the several pairs of dampers, the following construction is employed: Extending longitudinally beneath the girders 18 and likewise below the several cross ducts, are a plurality of operating shafts, there being a single shaft for each pair of associated dampers. As a preferable arrangement, a telescopic construction is employed; that is to say, tubular shafts, one inclosed within another and rotative independently of each other, are connected with the several pairs of dampers, each shaft extending from a common point 100 at the forward end of the stoker rearwardly to a point just beyond the dampers to be operated thereby. These shafts are preferably arranged as follows (Figs. 2, 6, and 7): The innermost shaft 71, preferably solid, 105 extends rearwardly to a point beneath the rearmost girder 18, where it is supported in a bearing 72. Surrounding the shaft 71 is a tubular shaft 73, likewise extending rearwardly but terminating just beyond the 110 next forward pair of cross ducts, said shaft being likewise journaled in similar bearings 72 mounted on the under side of the girder 18 adjacent its end. Likewise, surrounding the tubular shaft 73 is a tubular 115 120 125 130

shaft 74, slightly greater in diameter and extending rearwardly to a point just beyond the next pair of cross ducts, said tubular shaft 74 being journaled in bearings 72, as before. Surrounding the tubular shaft 74 is a still larger tubular shaft 75 extending rearwardly just beyond the front pair of cross ducts and likewise journaled in bearings 72 in the same manner as are the other shafts. As already suggested, each shaft is operatively connected to its associated pair of dampers, the following construction being preferably employed for connecting each pair of dampers to its operating shaft. Mounted on each shaft is a lever arm 76, located immediately below each damper and rigidly secured to the operating shaft and connected to the damper (Fig. 5). Each damper is provided 20 with an arm 77 extending outwardly therefrom at right-angles and preferably located adjacent to the lower margin thereof. Connecting the ends of the lever arm 76 and the arm 77 of the dampers is a link 78, preferably arranged in vertical position. By means of this form of connection it is observed that by rotating one of the shafts in one direction the dampers connected thereto will be swung outwardly from their closed 30 position, and by rotating said shafts in the opposite direction the dampers will be swung into closed position. As a preferable means of operating the damper-operating shafts independently of each other, a series of controlling levers are employed. These levers are arranged as follows: As before pointed out, the forward ends of the shafts terminate adjacent to the front end of the furnace and substantially at the same point, 40 although as a preferable arrangement each shaft extends a short distance beyond the shaft immediately surrounding the same, thereby providing at the end of each shaft a bearing surface, upon which is mounted a lever 79. These levers are operated by hand, the shafts being located preferably adjacent to one of the side frame members, thereby permitting access to the levers through a convenient opening in the side 50 frame members.

The operation and purpose of the construction herein described will be more clearly understood from the following: As is common in stokers of the type illustrated, 55 as well as in the ordinary stationary grate, the space below the active grate surface, generally termed a free air space, communicates with the atmosphere through the front end of the furnace, and through this source 60 delivers free air to the fuel bed. Where forced draft is used, it is desirable to shut off the supply of free air or natural draft to the fuel bed and to deliver air under pressure to the grate. In the construction herein 65 illustrated and described, this free air

space extends throughout the active grate area and between the upper and lower leads of the grate, and communicates with the atmosphere through the front portion of the stoker, in the usual manner, the air being drawn upwardly through the lower lead of the grate and into the space between the upper and lower leads and thence to the fuel bed. The arrangement of the girders, together with the hinged dampers, below the grate, provides in effect a series of spaces or chambers located in the free air space and inclosed by partition walls in the form of the girder webs and dampers. These spaces or ducts, which communicate with sources of forced draft, may be entirely inclosed or shut off from the free air space, by moving the dampers into closed position, thus rendering them inoperative. By swinging the dampers to open position, however, the forced draft spaces or ducts are not only opened to permit the delivery of air under pressure to the grate, but the entire free air space is converted into a forced draft space, the dampers forming a partition wall shutting off the space below the grate from the source of free air. The conversion of the free air space into forced draft space, it is to be noted, is accomplished without the diminution of the space available for the delivery of air uniformly throughout the grate area, this being due to the novel arrangement of the pairs of ducts, which permits them to open in a manner likened to the opening of a number of fans spaced apart end to end, whereby the area or air space is merely rearranged so as to supply it with air from either a source of natural draft or a source of forced draft.

By reason of the independent operation of the damper controlling mechanism, it is possible to operate the furnace under both natural and forced draft, by simply opening dampers of one or more pairs of dampers, retaining the remainder in closed position. This mode of operation is often desirable, where the combustion in certain portions of the grate area is such as to require an increased draft, as for instance where the fuel bed is thicker, or for other reasons which make the natural draft insufficient to promote proper combustion.

The principal advantages of a construction such as herein described lie chiefly in the simplicity and low cost of construction, 120 inasmuch as the permanent elements of the stoker frame are utilized to form a large portion of the ducts, for instance the cross ducts consist largely of the girders 18 of the stoker frame, requiring only the addition of 125 the dampers to form the ducts. The further advantage is the simplicity of operation and performance of the dampers, in that an arrangement of rotative shafts, connecting levers, and links is only necessary for the op- 130

eration of said dampers. Here, again, the permanent members of the stoker are utilized to aid in the functioning of the dampers, namely, the rollers, which serve as bearing members for the dampers and also to seal the air spaces formed by said dampers, thereby eliminating the additional bearings or sealing members, as well as a more positive type of operating mechanism to effect 10 the closing and sealing of the ducts and air spaces.

Although the novel construction is embodied in a chain grate stoker of the removable type, it is apparent that the same construction is applicable to a stoker of the non-removable type, and even to the ordinary stationary grate. As regards the removable type of stoker, the addition of the cross ducts and longitudinal ducts interferes in 20 no way with the removable stoker, inasmuch as the air boxes are easily disconnected at their rear ends from the main duct and the stoker drawn out from the furnace in the usual way.

25 Owing to the adaptability of this invention to all types of furnaces, as hereinbefore set forth, and for the reason that the construction herein described and illustrated may be modified without departing from 30 the spirit of the invention, it is not desired to limit this invention, except in so far as set forth in the appended claims.

I claim as my invention:

1. In a furnace, the combination of a 35 grate provided with a free air space therebelow, a plurality of forced draft ducts in said free air space, dampers normally closing said forced draft ducts and located in opposed relation to each other, said dampers 40 being movable toward each other in said free air space and adapted to form a partition wall shutting off the space between said forced draft ducts from communication with a source of free air.

45 2. In a furnace, the combination of a grate, a plurality of forced draft ducts extending transversely and arranged in spaced relation beneath said grate, there being provided a free air space between said ducts, 50 and a damper associated with each of said forced draft ducts, adapted to be moved in a direction toward each other to close said free air space.

3. In a furnace, the combination of a 55 grate, a plurality of forced draft ducts arranged in parallel and spaced relation beneath the grate, there being provided free air spaces intermediate said ducts, the latter being provided with oppositely disposed 60 openings, and dampers normally closing said openings from communication with said free air spaces and movable in a direction toward each other and into said free air spaces to shut off the supply of free air 65 thereto.

4. In a furnace, the combination of a grate, a plurality of forced draft ducts extending transversely and arranged in spaced relation throughout a free air space beneath the grate, there being provided free air passages between said ducts communicating with said free air space, said ducts being provided with oppositely disposed openings, and dampers mounted on said ducts and normally adapted to close said openings and 70 to be swung outwardly toward each other, 75 to close said free air passages.

5. In a furnace, the combination of a grate, a plurality of parallel girders extending beneath said grate and in the free air 80 space therebelow, a pair of cross ducts associated with each of said girders and comprising vertically arranged dampers hinged on opposite sides of each girder, said dampers being movable to open said cross ducts 85 to communication with said free air space and into a position to shut off the supply of free air to said air space, and means for supplying forced draft to said ducts.

6. In a furnace, the combination of a 90 grate, a supporting girder extending transversely beneath said grate and comprising a vertical web and a horizontal web, a vertically arranged damper hinged to the margin of said horizontal web and in one position 95 inclined toward the vertical web of said girder to provide an inclosed duct and movable away from said vertical web to open communication with a free air space beneath said grate and close the latter from communication with a source of free air, and means for supplying forced draft to said duct.

7. In a furnace, the combination of a 105 traveling grate, a supporting roller engaging the under surface of said grate, a plurality of forced draft ducts beneath said grate and on opposite sides of said supporting roller, said ducts having oppositely disposed openings adapted to communicate 110 with a free air space intermediate said ducts, and dampers normally closing said openings and movable toward each other and into contact with said supporting roller to close said air space.

8. In a furnace, the combination of a 115 grate, a plurality of parallel girders extending beneath said grate and in a free air space therebelow and provided with laterally extending webs, vertically arranged 120 dampers hinged upon the outer margins of said webs, said dampers being adapted to be swung into one position to form a duct adjacent each of said girders and into another position to shut off the supply of free air to 125 said air space, and means for supplying forced draft to said ducts.

9. In a furnace, the combination of a 130 traveling grate, transverse supporting rollers spaced apart beneath said grate, forced

draft ducts mounted in the free air space beneath said grate and in vertical alinement with alternate rollers, said ducts being provided with oppositely disposed openings, and 5 dampers adapted to close said openings and movable outwardly toward and into bearing engagement with the supporting rollers intermediate said ducts.

10. In a furnace, the combination of a traveling grate, girders extending transversely beneath the grate, a plurality of supporting rollers, there being a roller intermediate said girders, dampers hinged adjacent to said girders and adapted to have 15 bearing engagement with the rollers associated with said girders to form ducts and movable into contact with the roller intermediate said girders to close the air space between the girders, and means for supplying 20 forced draft to said ducts.

11. In a furnace, the combination of a traveling chain grate, a supporting frame, comprising side frame members, girders extending transversely between said side frame members and between the leads of said grate, supporting rollers mounted beneath the upper lead of said grate, there being a roller located in vertical alinement with each of 25 said girders and a roller intermediate said 30 girders, a plurality of pairs of cross ducts, each pair extending transversely on opposite sides of each girder and comprising dampers hinged along their lower margins to said 35 girders and normally engaging the roller adjacent the associated girder, means for 40 operating the dampers of each pair of ducts in a direction outwardly and into contact with the rollers intermediate said girders, and means for supplying forced draft to said ducts.

12. In a furnace, the combination of a chain grate, a supporting frame comprising side frame members and transverse girders extending between the leads of said grate, 45 having a vertical web and a lower horizontal web extending outwardly from both sides

of said vertical web, a plurality of rollers supporting said grate, there being a roller located in vertical alinement with each of said girders and a roller intermediate said 50 girders, a plurality of dampers hinged to the horizontal webs of each girder and inclined upwardly in bearing engagement with the rollers adjacent each girder, and means for swinging said dampers outwardly from 55 contact with said last mentioned rollers and into bearing engagement with the intermediate rollers.

13. A furnace stoker, comprising a traveling chain grate, a grate supporting frame 60 movably mounted within the furnace, air ducts extending transversely of said frame and between the upper and lower leads of said grate, an air box extending longitudinally of said frame and provided with a 65 plurality of air passages, each communicating with separate cross ducts, a main air supply duct fixed in the furnace and provided with an outlet opening communicating with said air box, and means for detachably 70 connecting said air box and main supply duct.

14. A furnace stoker, comprising a traveling chain grate, a supporting frame removably mounted in the furnace, a plurality of air ducts extending transversely of said frame, an air box extending longitudinally of said frame and provided with a plurality of separate air passages communicating with said air ducts, said air box extending beyond 80 one end of said grate, and a main supply duct permanently mounted in the furnace and having detachable connection with said air box.

In testimony that I claim the foregoing 85 as my invention, I affix my signature in the presence of two witnesses, this 1st day of March, A. D. 1917.

ARTHUR P. STRONG.

Witnesses:

ALEXANDER F. BUCK, Jr.,
HERMAN TORRENTON.
